UNITED STATES PATENT OFFICE

ARTHUR J. LEHMAN, OF CANNELTON, INDIANA

DESIGN FOR A COMBINED GLIDER AND SUPPORT

Application filed November 5, 1930. Serial No. 37,555. Term of patent 14 years.

To all whom it may concern:

Be it known that I, ARTHUR J. LEHMAN, a citizen of the United States of America, residing at Cannelton, in the county of Perry and State of Indiana, have invented a new, original, and ornamental Design for a Combined Glider and Support, of which the following is a specification, reference being had to the accompanying drawing, forming a part hereof.

In the drawing:

Figure 1 is a front elevation of a combined glider and support showing my new design, and

Fig. 2 is an end view of the same.

I claim:

The ornamental design for a combined glider and support, as shown.

ARTHUR J. LEHMAN. [L. S.]
